US00D852262S

(12) **United States Design Patent** (10) **Patent No.:** **US D852,262 S**
(45) **Date of Patent:** **** Jun. 25, 2019**

(54) **LORGNETTE**

(71) Applicant: **Incognito International LLC**,
Nokomis, FL (US)

(72) Inventor: **Sheryl Lynne Ford Bratton**, Nokomis,
FL (US)

(73) Assignee: **Incognito International LLC**,
Nokomis, FL (US)

(**) Term: **15 Years**

(21) Appl. No.: **29/626,605**

(22) Filed: **Nov. 17, 2017**

(51) **LOC (11) Cl.** **16-06**
(52) **U.S. Cl.**

USPC **D16/302**

(58) **Field of Classification Search**

USPC D16/301, 302, 303, 306

CPC G02C 3/04

See application file for complete search history.
